Attorney, Agent, or Firm—Leonard Bloom[57] **CLAIM**

The ornamental design of a computer mouse, as shown and described.

DESCRIPTION

FIG. 1 is a perspective view of a computer mouse showing my new design, the broken lines are for illustrative purposes only and form no part of the claimed design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a top view of a second embodiment of the computer mouse, corresponding substantially to FIG. 2, but showing the “clickers” on the other side of the mouse; and,

FIG. 9 is a left side view of a third embodiment of the computer mouse, corresponding substantially to FIG. 7, but showing a single round clicker.
